(57) **CLAIM**

The ornamental design for a fluid dispenser, as shown and described.

DESCRIPTION

FIG. 1 is a top, front, and left side perspective view of a fluid dispenser showing our new design;

FIG. 2 is a left side elevational view thereof;

FIG. 3 is a front elevational view thereof;

FIG. 4 is a right side elevational view thereof;

FIG. 5 is an additional top, front, and left side perspective view thereof;

FIG. 6 is an additional left side elevational view thereof;

FIG. 7 is an additional front elevational view thereof; and,

FIG. 8 is an additional right side elevational view thereof.

The broken-line disclosure, which is understood to represent portions of the article in which the claimed design is embodied, and which differs slightly between the disclosures of FIGS. 1–4 and 5–8, forms no part of the claimed design.
